UNITED STATES PATENT OFFICE.

CHARLES A. SHATTUCK, OF BOSTON, MASSACHUSETTS.

SUSPENDERS.

SPECIFICATION forming part of Letters Patent No. 375,010, dated December 20, 1887.

Application filed April 16, 1887. Serial No. 235,044. (No model.)

To all whom it may concern:

Be it known that I, CHARLES A. SHATTUCK, of Boston, in the county of Suffolk and State of Massachusetts, have invented certain 5 new and useful Improvements in Suspenders or Garment-Supporters, of which the following is a specification.

This invention relates to means for relieving strain on garment suspenders or supporters of that class in which are combined a normally open or extended spring and supporting devices therefor adapted for attachment to parts of suspenders, the arrangement being such that the spring is compressed or contracted by strain exerted on the suspenders, and therefore becomes, when contracted to its 15 utmost extent, a stop to limit the extension or yielding of the suspenders.

The invention consists in the improved devices, which I will now proceed to describe.

Of the accompanying drawings, forming a part of this specification, Figure 1 represents a front view of a suspender-end embodying my invention. Fig. 2 represents a rear view 25 of the same. Fig. 3 represents a side view of a part thereof.

The same letters of reference indicate the same parts in all the figures.

In the drawings, *a* represents a slide or buckle adapted to be engaged with the webbing of suspenders, or with any strap for garment-supporting purposes. From the lower edge of said slide project downwardly two parallel rods or guides, *b b*, which are preferably 30 united at their lower ends by a curved neck, the whole forming a **U**-shaped extension made integral with the slide or buckle, said slide and the rods *b b* being stamped out of a piece of sheet metal. On the rods or guides *b b* is placed a spiral spring, *c*, which follows the **U** shape of the guides, and is normally open or extended, as shown.

d represents a slide which is adapted to move upon the guides *b b*, and is supported by the spring *c*, the slide having ears *d' d'*, Fig. 2, bent around the guides and forming sockets which rest upon the ends of the spring. The slide *d* is also formed to be engaged with the straps *f f*, which are buttoned to the waist- 45 band of pantaloons in suspenders. In the 50 present instance a portion of the slide is bent

to form an eye, *g*, through which passes the cord or woven strip of which the straps *f f* are composed, said straps being in this case made in one piece, which is capable of sliding 55 in the eye *g*.

It will be seen that when the slide or buckle *a* is attached to the main strap of a suspender, or to any garment-supporting strap, and the straps *f f* are secured to the garment to be 60 supported, a longitudinal strain exerted on said straps will compress the spring, and thus elongate the suspenders, the elongation being permitted until the spring reaches its limit of compression, whereupon the spring becomes 65 a stop to prevent further elongation.

The slide or buckle *a* is made in a single piece, and is cut away at two places to form upper and lower cross-bars, *i j*, and a central cross-bar, *k*.

I form upon the upper cross-bar, *i*, a series of spurs or prongs, *l l*, projecting partly across the slot between said upper cross-bar and the central bar. When the main strap of the suspender is passed through the slots between the 75 cross-bars, the spurs enter said strap and prevent the slide or buckle from slipping downwardly thereon, but offer no resistance to the upward movement of the slide upon the strap. The slide can therefore be quickly adjusted, 80 and secures itself at any point to which it may be adjusted.

I claim—

1. The slide or buckle *a* and the **U**-shaped guides *b b*, all formed in one piece, as described, 85 combined with the single spiral spring *c*, following the curvature of the guide and extending along both arms thereof, and the slide *d*, having the hook *g*, and the sockets *d' d'*, adapted to slide on the guides, as set forth. 90

2. The slide or buckle *a*, having the cross-bars *i j k*, spurs *l l*, and **U**-shaped guides *b b*, all formed in one piece, as described, combined with the slide *d* and spring *c*, as set forth.

In testimony whereof I have signed my name 95 to this specification, in the presence of two subscribing witnesses, this 24th day of March, 1887.

CHAS. A. SHATTUCK.
